UNITED STATES PATENT OFFICE

MICHAEL A. ROLLMAN, OF MOUNT JOY, PENNSYLVANIA

ELECTRIC PLUG

Application filed May 15, 1928. Serial No. 277,865.

The object of this invention is to provide the plug with a handle which may be used for pulling it out of and putting it into the socket, to thus relieve the conductor of strain, this handle being laterally flexible so as to protect the corded conductor from injury by frequent bending at the point of connection with the plug, as more fully hereinafter set forth.

10 In the drawings—

Fig. 1 is a side elevation of my device complete;

Fig. 2 is a view partly in side elevation and partly in longitudinal section;

15 Fig. 3 is a sectional perspective view of the knob at the end of the handle.

Referring to the drawings annexed by reference characters, 5 designates the body of the plug which carries, in the usual manner, 20 the two terminals 6 adapted to enter the usual slots in the socket part 7 of the plug outfit. The plug 5 is provided with a central passage through which the corded conductor 8 passes, the two wire conductors enclosed therein being respectively connected to the usual binding-screws 9.

The bore of the plug 5 is threaded internally, and into this threaded portion of the bore is screwed the inner end of a spirally-ribbed armor 10 of well-known type. This armor is made, as usual, of a strip of sheet metal flanged and wound spirally, with a little lost motion in the joint to give flexibility, so that the tubular armor may flex 35 in any direction with respect to the socket, as shown in dotted lines in Fig. 1. The inner end of the spiral tube 10 is anchored in the socket by having its extreme inner edge reamed or flanged over at 11 against the interior shoulder formed in the bore of the socket, thus preventing the spiral tube from being pulled out of the socket. To lock the tube against being screwed into the socket, I provide a binding-screw 12 threaded through 40 the wall of the socket and having its inner end

bind against the interior surface of the tube.

The tube 10 is made of suitable length to serve as a handle, and attached to the outer end is a pulling-knob 13, preferably of insulating material. This knob 13 is fastened 50 to the spiral tube 10 in the same manner that the socket 5 is fastened thereto, i. e., by screwing the tube into the ring-like knob and having its extreme outer edge peened over at 14, a lock-screw 15 being threaded through 55 the knob in binding relation with the tube to thus lock the knob against being screwed inwardly on the tube.

As will be seen, the tube 10 and the knob 13 form a handle for use in disconnecting the 60 plug as well as pushing it into place in the socket. The making of the tube 10 flexible enables it to flex in any direction, to thus prevent injury to the textile covering of the conductor 8 in the manipulations of the plug. 65 The knob 13 is important in that it provides a good grip for the handle. The manner of fastening the ends of the tube 10 into the plug at one end and into the pull-knob 13 at the other end not only conduces to simplicity 70 and inexpensiveness, but provides a sure, long-lasting connection.

What I claim as new is:

1. In combination with a plug provided with a pair of terminals and having an internally-threaded bore, a spiral flexible tube threaded into said bore and secured therein by flanging over the end of the tube against an internal shoulder in the bore, and a binding- or set-screw carried by the plug and 75 adapted to bear against the tube to thus assist in locking the tube in the plug.

2. In an electrical plug, a body carrying the terminals and having a bore or hole, a spiral flexible tube fastened in said bore, and 85 a pull-knob screwed onto the outer end of said tube and secured thereto by having its extreme outer edge flanged-over upon the knob, a set-screw being employed to lock the knob to the tube. 90

3. An electrical plug embodying a plug-body having an internally-threaded bore, a flexible spiral armored tube screwed into said bore and locked therein by flanging-over the inner end of the tube, and a pull-knob at the outer end of said flexible tube fastened thereto by being screwed thereon and having the outer end of the tube flanged-over on the knob.

10 In testimony whereof I hereunto affix my signature.

MICHAEL A. ROLLMAN.
